United States Patent

Des. 241,341

Patented Sept. 7, 1976

241,341

ELECTRICAL CONNECTOR

Robert Frederick Oxley, 8 Rue Pedro-Meylan,
Geneva 1208, Switzerland

Filed Feb. 25, 1975, Ser. No. 553,033

Claims priority, application Great Britain Aug. 29, 1974

Term of patent 14 years

Int. Cl. D13—03

U.S. Cl. D26—1 A

FIG. 1 is an exploded view of an electrical connector according to my design;

FIG. 2 is a side elevational view thereof; and

FIG. 3 is an exploded view of a second embodiment of my design.

I claim:

The ornamental design for an electrical connector, substantially as shown and described.
